UNITED STATES PATENT OFFICE.

EDWIN G. HEATH, OF CONCORD, NEW HAMPSHIRE.

ADJUSTABLE SHADE HOLDER.

Application filed December 1, 1922. Serial No. 604,216.

To all whom it may concern:

Be it known that I, EDWIN G. HEATH, a citizen of the United States, residing in the city of Concord and State of New Hampshire, have invented new and useful Improvements in Adjustable Shade Holders, of which the following is a specification, reference being had to the accompanying drawings.

10 This invention is in the nature of an adjustable holder for window shades, and the object is to provide a simple, practical and efficient device for supporting ordinary window shades upon the window casements. 15 Another object is to provide such a holder in the form which may be readily and releasably attached to any standard window frame, without the use of nails or screws and without marring the frame work. A 20 still further object is to furnish a shade holder adapted for supporting the shade either inside the casement or on the outside face thereof, or two shades at the same time, one inside and the other outside the 25 casement.

In the drawing:

Figure 1 is an end view of one of the holders (there being one for either end of the top facing of the casement), shown 30 with the lever bracket raised and the upper and lower jaws extended for embracing the facing strip, the form of lever bracket here shown being adapted to support the shade roller outside the casement.

35 Figure 2 is a similar end view of the same form of holder, shown with the lever bracket depressed flat to the facing strip, and the upper and lower jaws thus drawn up tightly into engagement with the edges 40 of the facing strip.

Figure 3 is a frontal view of the device as shown in the end view in Figure 1.

Figure 4 is a frontal view of the device as shown in end view in Figure 2.

45 Figure 5 is a detail of the upper jaw of the form of holder shown in the preceding views.

Figure 6 is a detail of the lower jaw.

Figure 7 is a detail of the lever bracket.

50 Figure 8 is a detail of the connecting link extended between the lever bracket and the upper jaw.

Figure 9 is a rear view of the assembly of lower jaw, lever bracket and connecting

link for upper jaw, the lever bracket being 55 here shown raised as in Figure 1.

Figure 10 is a view similar to Figure 9, with the upper jaw hooked onto the upper end of the connecting link.

Figure 11 is a detail view of a modified 60 form of lever bracket, adapted to close down inside the casement frame, so as to support the shade roller with its ends inside the frame.

Figure 12 is a detail of a modified form 65 of lever bracket, having two roller supporting brackets, one adapted to close down inside the casement frame, as in Figure 11, and the other to lie flat against the outer face of the casement, as represented in the 70 first ten views.

Figure 13 is a detail of a modified form 75 of upper jaw, showing a series of transverse pins instead of the slots shown in Figure 5 and other figures.

Figure 14 is a detail of a modified form of lever bracket, showing a transverse pin mounted at the upper end, instead of a slot cut therein as represented in Figure 7 and other views.

Figure 15 is a detail of a modified form 80 of lever bracket, showing a curtain hook substituted on the outer or lateral extension thereof in lieu of the shade supporting stem shown in Figure 12.

The invention consists of a pair of jaws 85 formed preferably of sheet metal, an upper jaw 1 and an offsetting lower jaw 2, each having teeth 3 adapted to grip the upper and lower edges respectively of the casement 90 facing strip 4. If made of sheet metal, the side edges of the jaws may be turned out perpendicularly, as shown at 5, both in order to strengthen the structure and to facilitate connecting the elements together. 95

The upper jaw shank is provided with a series of transverse slots 6 as hook-holds, or pins 7 may be substituted as shown in modified form in Figure 13, these pins being passed through the out-turned edges 5 at 100 each side. The lower jaw has a V-shaped recess or crotch 8 cut out at its upper end and at this same end the side edges 5 are extended and enlarged to form ears 9. A lever bracket 10, similarly formed of sheet 105 metal and having a similar V-shaped crotch 11 at its upper end and out-turned edges 5 and ears 12, is pivoted or hinged to the lower

jaw 2 by nesting the ears 12 within the ears 9 connecting the two by rivets 13. The bracket 10 is also provided immediately below the crotch 11 with a transverse slot 14, 5 or a pin 15 may be substituted, as shown in modified form in Figure 14. A connecting link 16 is hinged at 17 into the slot 14 or onto the pin 15, and has its free end turned to a hook 18 which is adapted to releasably 10 engage any one of the series of slots 6, or the pins 7, according to the form of construction adopted. The lever bracket 10 may be formed with the lateral extension 19 and a final out-turned stem 20 with the 15 usual eye 21 for engaging the usual pivot pin in the end of the ordinary form of shade roller; and this form of construction is adapted to support the shade flatly against the outer face of the casement and so that 20 the shade will extend laterally over the facings of the casement in a well known way. This construction is illustrated in the first ten figures of the drawing. Or, as shown in Figure 11 the bracket may be formed 25 with the inwardly and downwardly turned extension 22 and then with the same final out-turned stem 20 with eye 21 therein as shown in Figure 7; and this form of construction is adapted to support the shade inside the casement. Or, as shown in Figure 30 12, the two preceding forms may be combined and the lever bracket provided with both the lateral extension 19 and stem 20, and also with the downward extension 22 35 and stem 20, for supporting two shades, one outside and one inside the casement. Or, as shown in Figure 15, a curtain hook 23 may be substituted on the lateral extension 19 of this combination form, in lieu of the shade supporting stem 20 shown in Figure 12, leaving the downward and inwardly turned extension 22 for supporting a shade.

In use, the jaws 1 and 2 of the device are spread or extended by raising the lever bracket 10 as far as possible and adjusting the jaws over the upper and lower edges of the facing strip 4 and then pressing the lever bracket down flat against the lower jaw, the leverage action or pull of the connecting link 16 being sufficient to contract or draw the two jaws 1 and 2 together and into engagement with the facing strip. As these facing strips may vary in width, an approximate adjustment of the device to 45 any width may be readily had by simply hooking the upper end or hook 18 of the connecting link 16 into the required one of the slots 6, or onto one of the pins 7 of the modified form. Of course it is understood that a holder is to be mounted at each 50 end of the facing strip for supporting both ends of the shade roller.

While I have herein described a certain specific method of constructing and assembling the elements of my invention, it is

understood that same may be varied in minor details, not departing from the spirit of my invention, as defined in the appended claims.

I claim:

1. An adjustable shade holder for a window casement, comprising an upper jaw and an off-setting lower jaw, adapted to grip the upper and lower edges of the upper facing strip of the casement, the upper jaw having a series of transverse slots therein as hook holds, and the lower jaw having a crotch at its upper end and side ears thereat; a lever bracket adapted at its lower end to support an end of a shade roller, and having a crotch at its upper end, a transverse slot immediately below the crotch, and side ears at the crotch nested and pivoted into the side ears of the lower jaw; and a connecting link having its lower end hinged through the slot of the lever bracket and its upper end formed into a hook adapted to releasably engage the upper jaw through any one of the slots thereof. 70

2. An adjustable shade holder for a window casement, comprising upper and lower jaws for gripping the facing strip, the upper jaw having transverse slots therein as hook holds, and the lower jaw having a crotch and side ears at its upper end; a lever bracket adapted at its lower end to support one end of a shade roller and having at its upper end a crotch, a transverse slot below the crotch and side ears pivoted within the side ears of the lower jaw; and a connecting link hinged through the slot of the lever bracket and having a hooked end adapted to releasably engage the upper jaw through any one of the slots thereof. 80

3. An adjustable shade holder for a casement, comprising upper and lower jaws for gripping the casement strip, the upper jaw having a series of transversely positioned pins thereon as hook holds, and the lower jaw having crotch and side ears at its upper end; a lever bracket having its lower end adapted to support an end of a shade roller and having at its upper end a crotch, a transverse pin below the crotch and side ears nested and pivoted within the side ears of the lower jaw; and a connecting link having its lower end hinged to the transverse pin of the lever bracket and its upper end hooked to engage the transverse pins of the upper jaw. 105

4. An adjustable shade holder for a casement, comprising upper and lower jaws for gripping the casement facing, the shank of the upper jaw having a series of hook-holds and the lower jaw having a crotch and side ears at its upper end; a lever bracket having its lower end adapted to support an end of a shade roller and having at its upper end a crotch and side ears nested and pivoted within the side ears of the lower jaw; and a connecting link having its lower end hinged 110 115 120 125 130

to the upper end of the lever bracket and its upper end hooked to releasably engage the hook holds of the upper jaw.

5. An adjustable shade holder for a casement, comprising upper and lower jaws for gripping the casement facing, the upper jaw being provided with hook-holds and the lower jaw with side ears at its upper end; a lever bracket with its lower end adapted 10 to support an end of a shade roller and its upper end having side ears pivoted to the ears of the lower jaw; and a connecting link hinged to the upper end of the lever bracket with its upper end hooked to engage the 15 hook holds of the upper jaw.

6. An adjustable shade holder for a casement, comprising upper and lower jaws for gripping the casement facing; a lever bracket hinged to the lower jaw and adapted to support one end of a shade roller; a connecting

link hinged by one end to the lever bracket; and means for releasably locking the free end of the connecting link to the upper jaw.

7. An adjustable shade holder for a casement, comprising upper and lower jaws; a 25 lever bracket hinged to the lower jaw and having a laterally turned extension for supporting an end of a shade roller outside the casement, and an inwardly and downwardly turned extension for supporting an end of 30 another shade roller inside the casement; a connecting link hinged by one end to the lever bracket; and co-operative means embodied on the connecting link and upper jaw for releasably locking the free end of 35 the connecting link to the upper jaw.

EDWIN G. HEATH.
